US00D483032S

(12) **United States Design Patent** (10) Patent No.: **US D483,032 S**
 Bertrand et al. (45) Date of Patent: ** Dec. 2, 2003

(54) **HOUSING FOR COMMUNICATIONS
DEVICES OR SIMILAR ARTICLES**

(75) Inventors: **Blaise Bertrand**, Milan (IT); **Tim Sutherland**, Gurnee, IL (US); **Theodore R. Arneson**, Mundelein, IL (US); **Ian James Myles**, Sunnyvale, CA (US)

(73) Assignee: **Motorola, Inc.**, Schaumburg, IL (US)

(**) Term: **14 Years**

(21) Appl. No.: **29/171,054**

(22) Filed: **Nov. 15, 2002**

(57) **CLAIM**

The ornamental design for a housing for communications devices or similar articles, substantially as shown.

DESCRIPTION

FIG. 1 is a front, side and top perspective view of an ornamental housing for communications devices or similar articles.

FIG. 2 is a first side elevation view according to FIG. 1.

FIG. 3 is a front elevation view according to FIG. 1.

FIG. 4 is a bottom plan view according to FIG. 1.

FIG. 5 is a top plan view according to FIG. 1; and,

FIG. 6 is a second side elevation view according to FIG. 1. The broken line portions of the drawings form no part of the claimed design.

1 Claim, 3 Drawing Sheets
